UNITED STATES PATENT OFFICE.

PETER I. LANGLYKKE, OF CHICAGO, ILLINOIS.

SPRING STRUCTURE FOR CUSHIONS.

1,352,977.

Specification of Letters Patent. Patented Sept. 14, 1920.

Application filed April 5, 1920. Serial No. 371,270.

To all whom it may concern:

Be it known that I, PETER I. LANGLYKKE, a citizen of the United States, residing at Chicago, in the county of Cook and State of Illinois, have invented certain new and useful Improvements in Spring Structures for Cushions, of which the following is a specification.

The invention relates to improvements in spring structures for cushions and the like.

One of the objects of the invention is to generally improve spring structures for cushions to render them more uniformly elastic or resilient and to provide means to 15 unfailingly maintain the helical springs thereof in upright positions or to so arrange them that they will always return to their parallel upright position when weight superimposed thereon is removed.

Another object is to provide fabric containers for the springs in which a separate pocket is provided for each spring and in which a series of such pockets, containing as many springs, may be inserted bodily in 20 a relatively long pocket of another fabric, spring container receptacle, thereby providing convenient means for repair and replacement of springs and the production of a spring cushion foundation that can be 25 made at a relatively low cost, because of the fact that the spring containers are made on sewing machines, there being practically no hand labor required in their production.

Other, further and more particular objects 30 of my invention will readily appear from a consideration of the following description when taken in connection with the accompanying drawing, wherein:—

Figure 1 shows a plan view of a complete 35 cushion foundation with a part of the outer receptacle broken away to show a series of spring containers therein.

Fig. 2 is a section taken on line 2—2 of Fig. 1.

Fig. 3 is a section taken on line 3—3 of Fig. 1.

Fig. 4 is an elevation of one of the spring containing pocket structures with part broken away showing a spring in one of the 50 pockets.

In all the views the same reference characters are employed to show like parts.

The springs 5 are of uniform diameter of

the helical type such as are used in structures of this general character. Each spring 55 is contained in a separate pocket such as shown at 6, in Fig. 4 and a series of spring pockets 6 are formed in a single container 7 and the containers filled with springs are placed in relatively long pockets 8 in the 60 fabric receptacles 9.

The spring containers 7 are each made, preferably, of a single piece of fabric, doubled over, as at 10, into a sort of bag formation, then the two side members 11 and 12 65 are sewed together forming vertical seams 13, spaced apart to form the pockets 6 to contain the springs 5, after the springs have been placed, each in a separate pocket. Then the two upper edges of the side members, 11 70 and 12, are sewed together, as at 14, to close the pockets.

A series of structures 7 are now to be placed in relatively elongated pockets 8 in the receptacle 9 as shown to the left in Fig. 75 2 and in Fig. 1. The receptacle 9 consists of an upper sheet 15 and a lower sheet 16. Strips 17 of proper height and length are first stitched to one of the sheets 15 or 16, as at 18, in spaced-apart relation, then the 80 other longitudinal edges of the strips 17 are properly spaced apart and stitched to the other sheet, as at 19. This can conveniently be done by beginning at the left and stitching the seams to the sheet in regular sequence. This forms the relatively long 85 pockets for the spring containers. After this has been done, then the edge strip 20 is sewed to the sheets 15 and 16, as at 21 and 22, respectively. One of the end strips 20 90 is left off until the containers 7 have all been placed in the pockets 8, then the end strip is stitched in place and the elongated pockets properly closed.

While I have herein shown a single embodiment of my structure for the purpose of clear disclosure, it will be manifest that changes may be made therein within the scope of the appended claim.

Having described my invention what I 100 claim as new and desire to secure by Letters Patent, is:—

A mattress structure having a plurality of inner coverings, each to contain a series of separated coil springs, each covering unit 105 comprising a single piece of fabric folded

in U-shape formation, said folds providing two vertical parallel side walls and a base wall, the latter as wide as the spring to be contained therein, said inner covering divided, at intervals, by vertical seams to provide a series of closed cylindrical pockets constituting a unit and a coil spring in each pocket and an outer covering comprising a

series of parallel stalls, each stall rectangular in shape with two side walls and a top 10 and bottom wall, whereby to provide four fabric walls between springs of adjacent units.

In testimony whereof I hereunto subscribe my name.

PETER I. LANGLYKKE.
